DESIGN FOR A SKIRT

Harry Zuckerman, New York, N. Y.

Application November 17, 1942, Serial No. 108,805

Term of patent 3½ years

To all whom it may concern:

Be it known that I, Harry Zuckerman, a citizen of the United States of America, residing in New York city, county of New York, and State of New York, have invented a new, original, and ornamental Design for a Skirt, of which the following is a specification, reference being had to the accompanying drawing, forming part thereof.

Fig. 1 is a front view of a skirt showing my new design.

Fig. 2 is a rear view thereof.

Fig. 3 is a fragmentary view of the front portion of the skirt as illustrated in Fig. 1 with the belt portion in open position.

I claim:

The ornamental design for a skirt, substantially as shown.

HARRY ZUCKERMAN.
